US00D997650S

(12) **United States Design Patent** (10) Patent No.: **US D997,650 S**
(45) Date of Patent: ** Sep. 5, 2023

(54) **CONTAINER**

(71) Applicant: **YETI Coolers, LLC**, Austin, TX (US)

(72) Inventors: **Dustin R. Bullock**, Austin, TX (US);
John Loudenslager, Austin, TX (US);
John Fritz, Austin, TX (US); **Michael**
Christopher Cieszko, Austin, TX (US);
Andrew J. Winterhalter, Austin, TX
(US)

(73) Assignee: **YETI Coolers, LLC**, Austin, TX (US)

(**) Term: **15 Years**

(21) Appl. No.: **29/849,054**

(22) Filed: **Aug. 8, 2022**

Related U.S. Application Data

(63) Continuation of application No. 29/737,275, filed on Jun. 8, 2020, now Pat. No. Des. 959,918, which is a continuation of application No. 16/218,089, filed on Dec. 12, 2018, now Pat. No. 10,766,672.
